UNITED STATES PATENT OFFICE

2,001,520

PRINTING MACHINE

Johan A. Carlson, Ashland, Mass., assignor to
Lucy F. Pratt, Ashland, Mass.

Application December 1, 1932, Serial No. 645,210

4 Claims. (Cl. 271—2.5)

This invention relates to a printing machine of that character in which a continuous strip or web of paper or like material, having strings attached to sections thereof is fed intermittently between co-operating printing members substantially as shown and described in United States Patent No. 1,318,108 dated October 7, 1919.

The present invention is an improvement upon the machine disclosed in the patent referred to, and has for its object to increase the efficiency of the same by avoiding interruptions in the use of the machine and consequent loss in production and time, and further has for its object to avoid injury to parts of the machine in transportation, assembling, and while in use as will be described.

The invention also has for its object to avoid imperfect printing of the tags or strung sections of the web or strip, as will be described.

These and other features of this invention will be pointed out in the claims at the end of this specification.

In the accompanying drawings,—

Fig. 1 is a vertical longitudinal section of the improved machine;

Fig. 2, an end elevation of the machine shown in Fig. 1, looking toward the left, the roll from which the tag strip or web is taken, being omitted;

Fig. 3, a plan view of the lower or bed portion of the machine, the side uprights of the framework being shown in section;

Fig. 4, an enlarged view in elevation of the guide members to be referred to, and

Fig. 5, a cross section on the line 5—5, Fig. 1, to illustrate the lock for the cover plate.

The printing portion of the machine is and may be substantially the same as in the machine disclosed in the patent referred to and comprises a stationary platen member *a*, and a reciprocating member *b* co-operating therewith.

The reciprocating member *b* comprises a chase 15 containing type 16 and secured to a plunger 17 connected with and operated by a path cam 25 in a disk 26 fast on a shaft 27 supported by the framework of the machine.

The type 16 are inked with printer's ink by one or more inking rollers 31 supported by the endless carrier in the form of parallel link chains 34, each of which passes over a sprocket wheel 35 fast on the shaft 27 and under sprocket wheels 36, 37, whereby the inking roller 31 on its passage beneath the reciprocating printing member *b* applies ink to the type 16.

During the passage of the inking roller 31 un-

der the reciprocating printing member, the latter is held stationary by the path cam 25.

The inking rollers 31 have co-operating with them an ink-distributing disk 40 pivoted to a support 42 and designed to be rotated by suitable lugs or projections, not shown, which are located on one of the link chains so as to rotate the disk 40 when an inking roller is out of contact with the said disk.

The base frame 29 of the machine is provided with a bed plate 54 of substantially the construction shown and described in the patent referred to and provided with an opening for the pad 60 on the stationary platen *a*.

The bed plate 54 is provided with a slot or channel, not shown, for the reception of the loops 52 of string carried by the unprinted strip or web 50, and is further provided with slots, not shown, up through which pass pins 91 for feeding the web 50 to the printing mechanism, as described in the patent referred to.

The feed pins 91 are carried by a plate 90 forming part of the feed mechanism, comprising a carriage slidably mounted in the base frame 29, and having a lug 85 connected by a link or rod 86 with a crank pin 87 on a disk 88 fast on a shaft 89, which is driven from the cam shaft 27. The feed pins 91 are raised by a cam 93 on a shaft 94 to engage the strung strip or web 50, between adjacent sections by entering notches 92 on opposite sides of the said strip or web. The pin plate 90 is lowered to withdraw the pins 91 from the notches 92 by a spring 104, when the strung strip or web has been fed forward into position to be printed.

The strip or web 50 with the loops 52 of string is fed from a roll 80, which for convenience is shown as a plain roll but which in practice is provided with the loops 52.

The strung strip or web 50 on its way to the printing mechanism passes under a cover plate 140 secured to a lever 141, pivoted to a support 142 fastened to a side of the framework.

The cover plate 140 forms with the bed plate 54 a guideway, and said cover plate, in accordance with the present invention, is extended beyond the front end of the bed plate and forms a substantially rigid upper guide member 200, which co-operates with a substantially rigid lower guide member 201, which is made as a bar or plate and is fastened to the upper surface of a metal block 202 secured as by screws 203 to the front end of the framework 29.

The guide members 200, 201 form a guideway 205 for the web or strip 50, which guideway is

practically a continuation of the guideway formed by the main portion of the cover plate 140 and the bed plate 54.

The rigid guide members 200, 201 are provided at the front ends with inclined surfaces 206, 207, which extends transversely of the members 200, 201 from one side to the other and register with each other to form rigid deflecting members for the loops 52 of string.

10 The upper guide member 200 has made integral with or secured to its inclined front edge a bar 209, preferably provided at its opposite ends with upwardly inclined and rounded portions which form noses 210 for facilitating the removal of any strings which may lie upon the upper surface of the web or strip 50.

The lower guide member 201 has made integral with or secured to it a similar bar 212 having rounded inclined noses 213 at its opposite ends.

20 The bars 209, 212 are arranged with their front faces flush with the inclined edges of the guide members 200, 201 so as to practically form vertical extensions of said inclined edges and thereby provide the guide members with auxiliary deflecting members of greater depth than the thickness of the inclined front edges of the guide members themselves, which construction affords a wide surface for the loops to engage and thereby facilitate the deflection of the strings which may extend across the web or strip toward the channel 215 in the upper guide member 200 and in the main or body portion of the cover plate.

25 The upper guide member 200 is normally positioned with relation to the lower guide member 201 to form the guideway 205 of a depth substantially equal to the thickness of the tag strip or web 50. This is effected by the vertical support 142 upon which rests the lever 141 carrying the cover plate.

30 In practice, the web 50 strung with loops 52 of strings is wound into the form of a roll, and the loops of string frequently extend across and under the web and adhere to the upper and lower surfaces of said strip or web, which is in a damp or moistened condition to enable it to be wound in the form of a roll.

35 The strings are more or less pressed into the moistened paper web or strip, and are separated therefrom by the upper and lower guiding members as the web or strip is fed forward toward the printing mechanism.

40 In the present instance, a partially unwound roll is shown, but in practice a roll of greater diameter than that shown in Fig. 1 is used when the machine is started in operation.

45 When a fresh or full roll is used, the strip 50 is led down to the guideway 205 and is fed into said guideway on an incline, indicated by the dotted line 220, Fig. 1.

50 As stated above, the web or strip 50 is fed intermittently toward the printing mechanism, and to prevent lifting of the upper guide member 200 and the cover plate 140 to which it is attached, a locking device is provided which co-operates with the upper guide member 200 to prevent the lifting action by the inclined web or strip as it is fed forward.

55 The locking device may and preferably will be made as herein shown and consists of a bar 221 (see Fig. 5), mounted to slide in a guideway located below the lower guide member 201 and formed by a bar 222 secured to the block 202 as by a screw 223, the sliding bar 221 being provided 75 with a finger 225 which projects over the cover

plate adjacent the upper guide member 200 so as to be engaged by the cover plate.

A very slight clearance between the finger 225 and the cover plate 140 is provided in order to permit the bar 221 to be manually moved to withdraw the locking finger 225 from above the cover plate, in case the operator desires to lift the cover plate to gain access to the strip or web beneath the same. The sliding bar 221 is made sufficiently long to provide a handle 227 to be grasped by the operator when he desires to unlock the cover plate.

60 The sliding bar 221 is automatically moved into its operative position by a spring 228 affixed to the block 202 at its lower end and having its upper end engaged with a pin 229 projecting from the sliding bar 221 (see Fig. 4).

The movement of the sliding bar 221 in opposite directions is limited by a pin 230 on the block or bar 222, which pin engages the end 15 walls of a notch 231 in the sliding bar 221 (see Fig. 5).

65 It will be observed that the locking device for the cover plate prevents the upper guide member 200 being lifted by the tag strip or web 50, and thereby prevents the guideway 205 between the guide members 200, 201 being enlarged sufficiently to allow the tag strip with a string or loop lying thereon to enter the guideway and be carried to the printing mechanism 30 and be printed upon by the latter and thereby produce a tag with imperfect printing thereon.

70 Provision is made for enabling the strung strip or web 50 to be passed through the guideway 205 and then under the cover plate with the latter in its lowered or operative position, with assurance that the notches 92 in the web or strip are properly positioned with relation to the feed mechanism so as to enable the feed pins 91 of the said mechanism when elevated by the cam 40 93, to enter the notches 92 in the strip or web.

75 For this purpose, the cover plate is provided with an opening 240 (see Fig. 3) which uncovers a notch 92 in one edge of the web or strip 50, and which opening is located in the cover plate 45 with respect to the feed pins 91 so as to ensure that the feed pins when elevated will enter notches 92 in the portion of the web or strip which is covered by the cover plate, and which notches are not visible to the operator without 50 lifting the cover plate so as to uncover the same, as is required in the machine disclosed in the patent above referred to.

80 By reference to Fig. 3, it will be observed that a notch 92 in the rear edge of the web or strip 50 is visible to the operator through the opening 240 in the rear edge of the cover plate, and when this occurs, the operator is assured that the web or strip fed by hand into the machine through the guideway 205 is properly placed so 60 as to be fed toward the printing mechanism by the feed pins 91.

85 The opening 240 in the cover plate avoids the necessity of the operator raising the cover plate and also avoids the necessity of the feed pins 91 being raised in order to position the notches in the web or strip 50 with relation to the feed pins 91. These operations require time and occasion economic loss to the user of the machine.

90 After a tag or section of the strung strip has been printed, it is cut from the continuous strip or web 50 in the manner described in the patent referred to.

95 From the above description, it will be ob- 75

served that the upper and lower guide members are of rigid construction and therefore are not liable to be bent or deranged by blows or jars, thereby avoiding delays in the use of the machine and the expense of repairs.

It will also be observed that imperfect work and also loss of time in threading the strung strip or web 50 into the machine is avoided by the lock for the cover plate, which ensures the upper guide member attached to the cover plate being maintained in proper relation to the lower guide member to form a guideway of the proper depth to permit the web or strip 50 to pass into the guideway and exclude the loops 52 of string, which are deflected toward the channels in the cover plate and bed plate by the rigid deflecting members.

This application is a continuation in part of application Serial Number 574,101 filed by me November 10, 1931, and which has matured into Patent No. 1,931,284, dated October 17, 1933.

What is claimed is:

1. In a printing machine of the character described, in combination, a bed plate over which is fed a strip or web strung with strings and provided with notches, a feed mechanism having means movable into and out of said notches for effecting intermittent feed of said strip or web, and a cover plate co-operating with said bed plate to form a guideway for said strip or web, said cover plate being provided with an opening with which a notch in the strip or web is capable of being registered to position the notches in the strip or web in proper position to be entered by said feeding means.

2. In a printing machine of the character described, in combination, a bed plate over which is fed a strip or web strung with strings, a cover plate co-operating with said bed plate to form a guideway for said strip or web, a rigid upper guide member attached to said cover plate and provided with an inclined front edge for deflecting the strings on the upper side of said strip or web, and an auxiliary deflecting member extended upwardly from the deflecting edge of said upper guide member.

3. In a printing machine of the character described, in combination, a bed plate over which is fed a strip or web strung with strings, a rigid lower guide member in line with said bed plate, a cover plate co-operating with the said bed plate and said guide member to form aligned guideways, a pivoted lever supporting said cover plate and extended laterally with relation to said cover plate, the front ends of said cover plate and said lower guide member being inclined transversely to form deflecting members for the said strings.

4. In a printing machine of the character described, in combination, a bed plate over which is fed a strip or web strung with strings, a rigid lower guide member in line with said bed plate, a cover plate co-operating with the said bed plate and said guide member to form aligned guideways, the front ends of said cover plate and said lower guide member being inclined transversely to form deflecting members for the said strings, and auxiliary deflecting members affixed to said cover plate and lower guide member and provided with round inclined ends.

JOHAN A. CARLSON. 25
